(57) **CLAIM**

The ornamental design for a bi-plane ceiling fan, as shown and described.

DESCRIPTION

FIG. 1 is a perspective view of an embodiment of the ceiling fan;

FIG. 2 is a first side view illustrating a representative side of the ceiling fan of FIG. 1;

FIG. 3 is a second side view illustrating a second representative side of the ceiling fan of FIG. 1;

FIG. 4 is a top view of the ceiling fan of FIG. 1; and,

FIG. 5 is a bottom view of the ceiling fan of FIG. 1.

The surface shading on the illustrated ceiling fan is intended only to show the character and contour of the surfaces and not as surface indicia.
